UNITED STATES PATENT OFFICE

2,294,575

PICKUP ARM FOR PHONOGRAHS

Emmor V. Schneider, Alliance, Ohio, assignor to
 Alliance Manufacturing Company, Alliance,
 Ohio, a corporation of Ohio

Original application September 11, 1940, Serial
 No. 356,313, now Patent No. 2,270,972, dated
 January 27, 1942. Divided and this applica-
 tion August 7, 1941, Serial No. 405,820

6 Claims. (Cl. 274—1)

The invention relates to electric phonographs and more particularly to certain improvements in the pick up arm in which is mounted the reproducer which carries the needle for recording or playing back a record, and the present application is a division of my co-pending application Serial No. 356,313, filed September 11, 1940, now Patent No. 2,270,972, granted January 27, 1942.

In recent years an increasing number of people have become interested in making their own records and playing the same as well as playing the usual commercial records, and this has resulted in a considerable demand for a moderate priced combination recording and play-back phonograph.

The object of the present improvement is to provide a simple, inexpensive pick up arm adapted for use in phonographs of the general character mentioned.

Another object is to provide a novel tension means for holding the pick up arm in either operative or inoperative position as desired.

A further object of the invention is to provide such a tension means which will function equally well upon a pick up arm designed for recording or reproducing, or a combination recording and reproducing arm.

A still further object is the provision of means whereby the pick up arm may be quickly and easily attached or detached when it is necessary to make repairs or replacements in the phonograph.

Still another object is the provision of means including a rotatable post for supporting the pick up arm, a channel shaped bracket upon the post and having notches in its outer end, a channel shaped pick up arm fitting over said bracket and interior studs pivoted in said notches and a pull spring connected to the outer end of the pick up arm and the inner end of the bracket for holding the pick up arm assembled upon the bracket.

A still further object of the invention is to provide a pick up arm as above referred to in which the tension spring is so located that it will normally hold the pick up arm in either position to which it is moved.

Another object is to provide a pick up arm of this character with an adjustable stop for limiting the downward movement of the pick up arm.

The above objects together with others which will be apparent from the drawing and following description, or which may be later referred to may be attained by constructing the improved pick up arm in the manner illustrated in the accompanying drawing in which

Figure 1 is a side elevation of a pick up arm constructed in accordance with the invention, parts being broken away for the purpose of illustration;

5 Fig. 2, a bottom plan view of the attaching bracket and the outer end portion of the pick up arm mounted thereon;

Fig. 3, a fragmentary view similar to Fig. 1, showing the pick up arm in the raised or inoperative position; and

Fig. 4, a detached, perspective view of the supporting bracket for the improved pick up arm.

Similar numerals refer to similar parts throughout the several views.

15 A portion of the platform of a phonograph cabinet is indicated at 10 and the usual turntable (not shown) may be rotatably supported upon said platform in any usual and well-known manner.

20 A bearing 11 is fixed upon the platform and has journaled therein the hollow shaft 12 through which may be located the electric cord 13 leading to the reproducer (not shown) mounted within the pick up arm indicated generally at 14.

25 The pick up arm may be of any usual and well-known design being preferably formed of sheet metal in the form of a stamping having the depending side flanges 15, front end 16 and rear end 17, and may house any suitable design of reproducer designed for either recording or playing back or combination of both.

For the purpose of mounting the pick up arm on the oscillating post 12 a channel shaped bracket indicated generally at 18 is fixed upon 30 the upper end of the post 12.

This bracket is provided with the upright flanges 19 at opposite sides, each flange having a notch 20 in its rear edge.

An ear or lug 21 is stamped up from the longitudinally central portion of the bracket 18 at a point near the forward end thereof.

40 Headed studs 22 are mounted in the side walls 15 of the pick up arm and are arranged to be received in the notches 20 at the rear edges of the vertical flanges 19 of the channel bracket 18.

45 A pull spring 23 has one hooked end 24 located through the slot 25 and aperture 26 in the upper rear corner of the pick up arm, the other hooked end 27 thereof being located through the aperture 28 in the ear 21 of the bracket 18.

50 The spring 23 is thus located at such an angle that with the pick up arm in the lowered or operative position as shown in Fig. 1, the spring 23 tends to urge the arm downward while when the arm is swung to the raised or inoperative posi-

tion shown in Fig. 3, the spring 23 moves from the point above the pivotal centers 22 to a point below the same, holding the arm in raised position.

For the purpose of adjusting the operative position of the pick up arm, an adjustable stop screw 29 is located through the internally threaded boss 30 fixed within the hollow pick up arm in suitable position so that the lower end of the adjusting screw 29 contacts the top of the bracket 18 when the pick up arm is in lowered position as shown in Fig. 1.

For the purpose of holding the stop screw 29 in adjusted position, a coil expansion spring 31 may be located within the bore 32 of the boss 30 interposed between the bottom wall thereof and the head 33 of the screw.

A needle as indicated generally at 34, of any usual and suitable design, for either recording or reproducing, as the case may be, may be carried by the reproducer (not shown) within the forward end of the hollow pick up arm and held in position in usual and well-known manner as by the set screw 35 received in the vertical slot 36 in the forward end wall 16 of the pick up arm.

In the position shown in Fig. 1, the pick up arm is in position for either recording or reproducing a record, the needle 34 being in position to engage the record upon the turntable (not shown).

When it is desired to raise the pick up arm from the record, it is swung upwardly upon the pivot points 22 to the position shown in Fig. 3, the spring 23 throwing over center as above described and holding the pick up arm in raised position until it is again manually lowered to the operative position.

I claim:

1. In a phonograph, a horizontal platform, a vertical post journaled in said platform, a bracket upon the top of the post and having notches open through its outer end, a hollow pick up arm having studs upon its interior detachably pivoted in said notches and a pull spring connected to the outer end of the pick up arm and to the inner end of the bracket for holding the pick up arm assembled upon the bracket and for holding the pick up arm in either angular raised or substantially horizontal lowered position.

2. In a phonograph, a horizontal platform, a vertical post journaled in said platform, a bracket upon the top of the post and having notches open through its outer end, a hollow pick up arm having studs upon its interior detachably pivoted in said notches and a pull spring connected to the outer end of the pick up arm and to the inner end of the bracket for holding the pick up arm assembled upon the bracket and for holding the pick up arm in either angular raised or substantially horizontal lowered position, and an adjustable stop carried by the pick up arm for contact with the bracket for limiting the downward movement of the pick up arm.

3. In a phonograph, a horizontal platform, a

vertical post journaled on said platform, a bracket upon the top of the post and having notches open through its outer end, a hollow pick up arm receiving said bracket and having studs upon its interior detachably pivoted in said notches, and a pull spring having one end connected to the outer end of the pick up arm above said studs and its other end connected to the inner end of the bracket below said studs so that the spring throws over center of the studs when the pick up arm is pivoted upon the studs, and holds the pick up arm in either angular raised or substantially horizontal lowered position.

4. In a phonograph, a horizontal platform, a vertical post journaled on said platform, a bracket upon the top of the post and having notches open through its outer end, a hollow pick up arm receiving said bracket and having studs upon its interior detachably pivoted in said notches, and a pull spring having one end connected to the outer end of the pick up arm above said studs and its other end connected to the inner end of the bracket below said studs so that the spring throws over center of the studs when the pick up arm is pivoted upon the studs, and holds the pick up arm in either angular raised or substantially horizontal lowered position, and an adjusting screw carried by the pick up arm for contact with the bracket for limiting the downward movement of the pick up arm.

5. In a phonograph, a horizontal platform, a channel shape bracket journaled upon said platform and having upright flanges at its side edges provided with notches open through their outer ends, a hollow pick up arm receiving said bracket and having studs upon its interior detachably pivoted in said notches, and a pull spring having one end connected to the outer end of the pick up arm above said studs and its other end connected to the inner end of the bracket below said studs so that the spring throws over center of the studs when the pick up arm is pivoted upon the studs, and holds the pick up arm in either angular raised or substantially horizontal lowered position.

6. In a phonograph, a horizontal platform, a channel shape bracket journaled upon said platform and having upright flanges at its side edges provided with notches open through their outer ends, a hollow pick up arm receiving said bracket and having studs upon its interior detachably pivoted in said notches, and a pull spring having one end connected to the outer end of the pick up arm above said studs and its other end connected to the inner end of the bracket below said studs so that the spring throws over center of the studs when the pick up arm is pivoted upon the studs, and holds the pick up arm in either angular raised or substantially horizontal lowered position, and an adjustable stop carried by the pick up arm for contact with the bracket for limiting the downward movement of the pick up arm.

EMMOR V. SCHNEIDER.
